(57) **CLAIM**

The ornamental design for an electrical connector, as shown and described.

DESCRIPTION

FIG. 1 is a front isometric view of an electrical connector showing our new design.

FIG. 2 is a rear isometric view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front isometric view thereof, shown in environmental use; and,

FIG. 10 is an exploded front isometric view thereof, shown in environmental use.

The broken lines in the figures illustrate the portions of the design that form no part of claimed design.

The broken line component of FIGS. 9 and 10 illustrate environmental subject matter that form no part of the claimed design.

None of the broken lines form any part of the claimed design.
